(57) **CLAIM**

The ornamental design for a broadhead, as shown and described.

DESCRIPTION

FIG. 1 is a front perspective view of a broadhead showing our new design;

FIG. 2 is a rear perspective view thereof;

FIG. 3 is a top view thereof;

FIG. 4 is a side view thereof;

FIG. 5 is a front view thereof; and,

FIG. 6 is a rear view thereof.

The right side view being identical to the left side view and the bottom view being identical to the top view, the redundant side and bottom views are not shown.

In the drawings, the broken lines depict environmental subject matter only and form no part of the claimed design.
